UNITED STATES PATENT OFFICE

2,644,396

AERIAL MISSILE

Louis S. Billman, Glastonbury, Conn., assignor to
United Aircraft Corporation, East Hartford,
Conn., a corporation of Delaware

Application October 1, 1948, Serial No. 52,170

9 Claims. (Cl. 102—49)

1

This invention relates to a combination pulse jet and ram jet.

It is well known that a ram jet is normally capable of sustained self-propelled motion only above a predetermined speed, and the vehicle incorporating the ram jet must be accelerated to a speed above that minimum before the ram jet will be effective. A feature of this invention is an arrangement for driving the ram jet by another type of power plant until it exceeds the predetermined minimum speed after which the ram jet is disconnected from the other power plant.

It is possible to ferry a ram jet by airplane until the desired minimum speed for the ram jet is reached, but with such an arrangement, the ferrying vehicle is not normally disposable by reason of initial cost and the presence of a pilot. A feature of the invention is the use of a low-cost, short-life power plant as the ferrying vehicle so that it may be expendable when the ram jet has reached operative speed.

One feature of the invention is an arrangement for automatically disposing of the accelerating or starting power plant by causing it to be ejected from the ram jet when the latter becomes operative.

Other objects and advantages will be apparent from the specification and claims and from the accompanying drawings which illustrate an embodiment of the invention.

Fig. 1 is a side view of the device.

Fig. 2 is a sectional view through the ram jet and the inlet end of the pulse jet.

Fig. 3 is a sectional view of the remainder of the missile.

Fig. 4 is a fragmentary view of a modified type of valve.

Fig. 5 is a developed sectional view substantially along the line 5—5 of Fig. 4.

Referring first to Fig. 1, the device includes a ram jet 2 having a thrust nozzle 4 within which a pulse jet 6 is partially enclosed. The ram jet may be provided with small stabilizing fins 8 adjacent the nose and other fins 10 and 12 adjacent the discharge end. The pulse jet carries larger stabilizing fins 14 which, as will be apparent later, are disposable with the pulse jet when the ram jet has been accelerated to an operative speed.

As shown in Fig. 2, the ram jet part of the missile includes a central substantially cylindrical member 16 which functions as a container for fuel and for the controls and which may carry a war-head 18, as will be apparent. The member 16 has a conical leading end 20 and a conical downstream end 22. The container is

surrounded by an outer shell 24 spaced from the container and defining an annular path 26 for the ram jet. Air enters the leading end of the annular space 26 and flows therethrough past fuel nozzles 28 located forwardly of the downstream cone 22. Struts 30 may support the shell in predetermined spaced relation to the inner member.

The thrust nozzle 4 forms a rearwardly projecting extension of the outer wall 24 which, as shown, may be double-walled with a space 32 therebetween. The inner wall 34 of the outer shell may be reduced in diameter adjacent to the cone 22 for a more effective path of flow for the gas through the ram jet. In the thrust nozzle 4, the inner wall of the outer shell 32 has an inner lining 36 (Fig. 3) closely spaced from the inner wall 34 to form a flow path for boundary layer air which enters at the forward end of the liner 36 and cools the liner and the inner wall. The lining 36 is spaced from the inner wall at its rearward end for the escape of boundary layer air. In order to provide proper spacing for the lining 36 conventional streamlined struts or spacers (omitted for convenience) may be utilized as for example struts similar to the spacing struts 30 mentioned above.

The pulse jet 6, which, as above stated, is located in part within the thrust nozzle 4, has inlet valves 38 at the forward end thereof supporting a central conical member 40 which fits over the end of cone 22 and limits the forward movement of the pulse jet within the thrust nozzle 4. A typical example of such valves is clearly shown in Patent No. 1,586,226 issued May 25, 1926. The valve 38 may comprise a group of flapper-type valves or reed type valves which may have a slight bias toward the closed position. Such valves are conventional and well known in the art. The valves 38 are supported at the forward end of a sleeve 42 which forms the combustion chamber 44 for the pulse jet and which is connected at its rearward end with the duct 46 forming the thrust nozzle of the pulse jet. The duct 46 carries rollers 48 engaging with the liner 36 and supporting the pulse jet for axial movement within the thrust nozzle 4. For improving the streamlining of the device, a frusto-conical sleeve 49 is mounted around the downstream end of the thrust nozzle 46 and engages at its forward end with the discharge end of the thrust nozzle 4. The sleeve 49 carries the fins 14, above mentioned, and provides for augmentation of the flow through the duct, the air entering said sleeve through the cooling air space around the liner 36, and also, if desired, through forwardly ar-

ranged openings 50 outwardly of the thrust nozzle 4 at the inlet end of the sleeve 49.

In operation, in starting the device, the pulse jet is set in operation by the ignition of fuel injected intermittently through nozzles 51, preferably located in the supporting structure for the ring of valves 38. The fuel may be supplied through passage 52 in the cylindrical member 16 and the valve structure. A suitable ignitor 53 is provided in the combustion chamber 44 to 10 ignite the fuel and thus provide for an intermittent discharge of gas through the thrust nozzle 46. Air enters the pulse jet by passing through the ram jet and provides for operation of the pulse jet for the purpose of starting the 15 missile in flight and for accelerating the ram jet to an operative speed for the ram jet. When the ram jet reaches operative speed, fuel is injected through the nozzles 28 by means of an airspeed responsive device which may have a predetermined airspeed or Mach number setting. Any of the well known spring loaded mechanisms or a diaphragm subjected to Pitot tube pressures may be utilized. The fuel is ignited either by the ignitor 53 or by the combustion in the chamber 44. In either event, the air passing through the ram jet ultimately exerts a rearward thrust on the pulse jet greater than the forward thrust exerted by the pulse jet and forces the pulse jet 20 axially rearwardly within the thrust nozzle 4 thereby ejecting it and allowing the ram jet to 30 become effective. Obviously, a suitable mechanism, not shown, provides for closing the fuel passage 52 when the pulse jet is ejected as for example by tripping a spring loaded valve in response to the actuating movements of above mentioned airspeed responsive device which actuates the fuel injection means for the ram jet. It will be apparent that the pulse jet is retained in the ram jet 4 only by the thrust exerted by the pulse jet, and, as the ram jet ram air pressure increases, the pulse jet is readily ejected. It should be noted that the static ram pressure in the ram jet will increase with continued increase in flight speed of the combined missile so that eventually sufficient ram pressure is developed to 35 eject the pulse jet. The entire operation is most clearly understood under the condition where the fuel is simultaneously injected into the ram jet and cut off in the pulse jet. It is apparent then that the thrust of the pulse jet will immediately drop toward zero so that the ram air pressure in the ram jet will suddenly eject the pulse jet unit.

Instead of a series of valves disposable with the pulse jet, the set of valves may be replaced by a bank of valves which remain in the ram jet, as shown in Figs. 4 and 5, in which the valve elements 54 are in the form of streamlined vanes pivoted on substantially radial axes and normally spring loaded into the closed position shown in dotted lines. When the pulse jet is discarded, these vanes may be automatically moved by a suitable linkage into the full-line position of Fig. 5 in which they offer only a small resistance to the flow through the ram jet.

It is to be understood that the invention is not limited to the specific embodiment herein illustrated and described, but may be used in other ways without departure from its spirit as defined by the following claims.

I claim:

1. A missile including an annular ram jet surrounding a container, said ram jet having an inlet at one end and a thrust nozzle at the opposite

end, means for introducing fuel to said ram jet between the inlet and the nozzle, and igniter means aft of said fuel means, in combination with a pulse jet fitting in part within said thrust nozzle, said pulse jet having its open inlet end located within the ram jet and forward of said igniter means to receive the gas from said ram jet, said pulse jet including a combustion chamber, and a thrust nozzle communicating with and receiving the gas from the combustion chamber, said pulse jet having means externally thereof for guiding it within the first thrust nozzle, said pulse jet being substantially free to move rearwardly for removal from the ram jet.

2. A missile including an annular ram jet surrounding a container, said ram jet having an inlet at one end and a thrust nozzle at the opposite end, means for introducing fuel to said ram jet between the inlet and the nozzle, and an igniter between said fuel means and the nozzle, in combination with a pulse jet fitting in part within said thrust nozzle, said pulse jet having means engaging with said container to limit its forward motion within said nozzle to a point upstream of said igniter, said pulse jet having its open inlet end located within the ram jet to receive the gas therefrom, said pulse jet including a combustion chamber, and a thrust nozzle communicating with and receiving the gas from the combustion chamber, said pulse jet having means externally thereof for guiding it within the first thrust nozzle, said pulse jet being substantially free to move rearwardly for removal from the ram jet.

3. A missile including an annular ram jet surrounding a container, said ram jet having an inlet at one end and a thrust nozzle at the opposite end, and means for introducing fuel to said ram jet between the inlet and the nozzle, in combination with a pulse jet fitting in part within said thrust nozzle, said pulse jet having its open inlet end located within the ram jet to receive the gas therefrom, a bank of valves adjacent the inlet end of the pulse jet for regulating the flow of gas thereto, said pulse jet including a combustion chamber, and a thrust nozzle communicating with and receiving the gas from the combustion chamber, said pulse jet having means externally thereof for guiding it within the first thrust nozzle including anti-friction elements engaging the nozzle, said pulse jet being substantially free to move rearwardly for removal from the ram jet.

4. A missile including a substantially annular container, a duct surrounding and spaced from said container to define an annular ram jet having an inlet at one end, the other end of the duct forming a combustion chamber and a thrust nozzle, said thrust nozzle being double walled with the space between said walls receiving boundary layer from the ram jet forwardly of the combustion chamber to provide for cooling the walls of the nozzle.

5. A missile including a substantially annular container, a duct surrounding and spaced from said container to define an annular ram jet having an inlet at one end, the other end of the duct forming a combustion chamber and a thrust nozzle, said thrust nozzle being double walled with the space between said walls receiving boundary layer from the ram jet forwardly of the combustion chamber to provide for cooling the walls of the nozzle, in combination with a pulse jet fitting, at least in part, within said thrust nozzle, means on said pulse jet and engag-

ing with the inner wall of the nozzle for guiding the pulse jet for axial movement within the nozzle, cooperating means on the ram jet and pulse jet for limiting the forward movement of the pulse jet relative to the ram jet.

6. A ram jet including a duct having an inlet passage at one end and a thrust nozzle at the opposite end, means for introducing fuel to said ram jet between the inlet and the nozzle, and means for igniting said gases, in combination with a pulse jet partially positioned within said nozzle, said pulse jet having its open inlet end located within the ram jet to receive the gas therefrom, said pulse jet including a combustion chamber having the gases therein ignited by said ram jet igniting means, and a thrust nozzle communicating with and receiving gas from the combustion chamber.

7. A ram jet combination according to claim 6 wherein said pulse jet includes valve means positioned upstream of the pulse jet combustion chamber and said ram jet igniting means.

8. A ram jet including a duct having an inlet passage at one end and a thrust nozzle at the opposite end, and means for introducing fuel to said ram jet between the inlet and the nozzle in combination with a pulse jet partially positioned within the nozzle end of said ram jet, said pulse jet having its open inlet end located within the ram jet to receive gas therefrom, means for introducing fuel into said pulse jet, guide means permitting axial separation of said pulse jet from said ram jet, and igniter means carried by said

ram jet locating the combustion chamber for both said ram jet and said pulse jet.

9. A ram jet including a duct having an inlet passage, a combustion chamber, and a discharge passage in the form of a thrust nozzle, in combination with a pulse jet including a duct having an inlet located within the discharge passage and adjacent the combustion chamber of the ram jet, a bank of valves in said pulse jet inlet and 10 a combustion chamber downstream thereof, said ram jet and pulse jet having cooperating means for limiting the forward movement of the pulse jet relative to the ram jet, and means for directing fuel from the ram jet to the pulse jet downstream of said valves.
